P. J. Berry
Attorney

UNITED STATES PATENT OFFICE.

ERNEST WILLIAM KLEIN, OF LOS ANGELES, CALIFORNIA.

COMMUTATOR.

Application filed February 14, 1922. Serial No. 536,471.

To all whom it may concern:

Be it known that I, ERNEST WILLIAM KLEIN, a citizen of the United States, residing at Los Angeles, in the county of Los Angeles and State of California, have invented new and useful Improvements in Commutators, of which the following is a specification.

My invention pertains to a commutator 10 of the type such as is employed with internal combustion engines in controlling and timing ignition of the explosive charge in the engine cylinders and particularly relates to the construction of the rotary contact member 15 in commutators of the character embodying an annular shell fitted with alternate sections of electrical conductive and non-conductive material over which a rotating contact element is passed.

An object of my invention is to provide a commutator with a rotary wiper contact member which is so constructed and arranged that the bearing surfaces will wear evenly and thereby insure proper make and 25 break of the electrical circuit controlled by the commutator, and in which the wiper contact member or brush is reversible so that when one portion thereof is excessively worn the brush may be turned to present another wearing surface.

Another object is to provide a wiper contact member embodying a spring pressed brush in which the spring is so arranged and connected to the brush that it may be 35 readily removed and replaced and when in place the parts maintained in proper position to permit ready assemblage of the commutator.

Another object is to provide a commutator 40 which is not liable to get out of order, which will endure considerable wear and accordingly obviate frequent replacement and repairs, and which can be economically produced.

With the foregoing objects in view, together with such other objects and advantages as may subsequently appear, my invention resides in the parts and in the construction, arrangement, and combination of 45 parts, or their equivalents, as hereinafter described and claimed and illustrated in the accompanying drawings, in which:

Figure 1 is a perspective view of the commutator with parts broken away.

Fig. 2 is a view of the rotary wiper 55 contact member as seen in side elevation.

Fig. 3 is a view of the wiper contact member as seen in vertical section.

Fig. 4 is a detail in perspective of the brush carrying guide sleeve.

More specifically 6 indicates a rotary timing shaft on which is mounted a removable collar carrying a guide-sleeve 8 in which a brush or wiper contact member 9 is slidably mounted. The guide-sleeve is of rectangular cross section as is the brush and is preferably formed of sheet metal as shown in Fig. 4 but may be made of cast metal if desired. The sleeve is here shown as comprising front and rear walls 10 and 11 connected together 70 by side walls 12 and 13 and is open at its ends. The back wall is formed with a slot 14 and a tongue 15 is provided which projects from the lower end of the slot and is curved to conform to the periphery of the 75 collar, and projecting upwardly from the lower end of the sleeve is a flange 16 the outer end of which is curved to conform to the underside of the collar. In mounting the sleeve on the collar the latter is formed 80 with a flat face 17 against which the back wall of the sleeve seats to provide a substantial bearing and the tongue and flange are positioned to extend on opposite sides of the collar and are engaged therewith preferably by welding. The collar and guide sleeve may however be formed in one piece.

The guide sleeve is thus positioned at one side of the collar and is of such length as to project beyond the opposite edges of the flat 90 face 17 so that the lower end of the guide-sleeve will extend below the collar and the upper end of the guide-sleeve will project thereabove. The flange 16 extends from the lower end of the guide-sleeve upwardly at an angle into contact with the collar and thus forms a space 18 rearward of the flange and formed in the flange is a slot 19 the lower edge of which is spaced from the point of intersection of the flange 100 and sleeve to provide a wall 20.

The wiper contact member is formed with an arcuate recess 21 intermediate its ends on one side thereof and is provided with a slot 22 leading therethrough from the center 105 of the recess.

A curved plate spring 23 is provided the lower end of which is formed with a reverse

curve and is inserted through the slot 19 into engagement with the wall 20 and the upper end of the spring is formed with a reversed curve or hook 24 which is passed 5 through the slot 14 in the guide-sleeve and engaged in the slot 22 in the brush. The spring is tensioned to exert an upward thrust on the brush to normally maintain the latter in its uppermost position and 10 cause it to bear against an annular flange 25 on a commutator cap fitted with a series of contact plates 26 set in an insulating wall 27. The outward movement of the brush under the action of the spring is limited by 15 the upper end of the slot 14 in the guide-sleeve engaging the spring which permits the commutator cap being removed without causing the brush to be ejected from the guide-sleeve. When the brush is in place 20 in the cap it is retracted sufficiently in the guide-sleeve to dispose the spring out of contact with the end of the slot.

The ends of the brush are rounded so as to conform to the curvature of the annular 25 flange 25 and are so formed that the brush may be positioned with either end outermost which permits the brush being reversed when one end becomes excessively worn.

By mounting the spring and brush as set 30 forth the brush may be readily removed and replaced as by depressing the brush the hook 24 on the spring may be easily disengaged from the brush and if it is desired to remove the spring the lower end thereof may be 35 easily withdrawn from the slot 19. Replacement of the spring may also be easily effected and may be accomplished without removing the brush from the guide-sleeve.

A recess 21 in the brush is provided for 40 the purpose of affording a thin wall on the margin of the slots 22 and also to provide a space in which the outer end of the hook 24 extends so that the hook will not project beyond the outer face of the brush. The 45 hook is formed with an arcuate upper face in which the edge of the slot seats, which permits the hook being readily disengaged from the brush.

I claim:

50 1. In a commutator, a rotary shaft, a guide-sleeve thereon, a brush wiper slidable in said sleeve, and a curved plate spring having one end arranged in hooked engage-

ment with said brush wiper and its opposite end in hooked engagement relative to the 55 shaft.

2. In a commutator, a collar, a guide-sleeve carried on said collar having a back wall formed with a slot adjacent one end thereof, a brush wiper slidable in said sleeve 60 formed with a slot, and a curved plate spring having one end in hooked engagement relative to the collar, said spring being formed with a hook on its outer end and engaged with the slot in the brush wiper through the 65 slot in said guide-sleeve and acting to exert an outward thrust on said brush wiper.

3. In a commutator, a collar, a guide-sleeve carried on said collar having a back wall formed with a slot adjacent one end 70 thereof, a brush wiper slidable in said sleeve formed with a slot, and a curved plate spring having one end in hooked engagement relative to the collar, said spring being formed with a hook on its outer end and engaged 75 with the slot in the brush wiper through the slot in said guide-sleeve and acting to exert an outward thrust on said brush wiper, the outer end of the slot in said guide-sleeve serving as an abutment to limit outward 80 movement of the brush wiper under action of the spring.

4. In a commutator, a collar, a guide-sleeve carried on one side of said collar formed with a slot adjacent one end thereof, 85 a flange extending from the opposite end of the guide sleeve to the collar formed with a slot, a wiper contact member slidable in said sleeve formed with a slot, and a curved plate spring, one end of which is engaged 90 in the slot in the flange, and the other end of which extends through the slot in the sleeve and is engaged in the slot in the wiper contact member.

5. In a commutator, a brush wiper comprising a bar formed with a recess on one side thereof and having a slot extending through the bottom wall of said recess for the purposes set forth.

6. In a commutator, a brush wiper comprising a bar formed with a recess on one side thereof and having a slot extending through the bottom wall of said recess and a plate spring having hooked engagement with the margin of said slot.

ERNEST WILLIAM KLEIN.
